Primary Examiner — Rosemary K Tarcza*Assistant Examiner* — Christy Nemeth(74) *Attorney, Agent, or Firm* — Gardner, Linn, Burkhart & Ondersma LLP(57) **CLAIM**

The ornamental design for a cargo net for a portable tower with electrical outlets, as shown and described.

DESCRIPTION

FIG. 1 is a front perspective view of a cargo net for a portable tower with electrical outlets showing our new design;

FIG. 2 is a front elevation thereof;

FIG. 3 is a rear elevation thereof;

FIG. 4 is a right side elevation thereof;

FIG. 5 is a left side elevation thereof; and,

FIG. 6 is a top plan view thereof.

The broken lines in the drawings are for the purpose of illustrating environmental subject matter that forms no part of the claimed design. A bottom view forms no part of the claimed design.
